THEOPHILUS F. BERTRAND AND PETER SAMES, OF ROCKFORD, ILLINOIS.

Letters Patent No. 60,916, dated January 1, 1867.

IMPROVEMENT IN CULTIVATORS.

The Schedule referred to in these Letters Patent and making part of the same.

TO ALL WHOM IT MAY CONCERN:

Be it known that we, THEOPHILUS F. BERTRAND and PETER SAMES, both of Rockford, in the county of Winnebago, and State of Illinois, have invented new and useful Improvements in Cultivators; and we do hereby declare that the following is a full, clear, and exact description of the construction and operation of the same, reference being had to the annexed drawings, making a part of this specification, in which—

Figure 1 represents a side elevation of our cultivator.

Figure 2, a plan view of the same; and

Figure 3, a section through the double standard block.

It is the object of our invention to simplify the cultivator and render it susceptible of easy adjustment to various crops and varying modes of cultivation; to which end our invention consists, first, in so combining a tongue and axle as that they alone shall constitute the main frame; second, in combining with the tongue a single cross-piece to support the levers by which the auxiliary frame is elevated or depressed, or retained in position; third, in combining two spring bolts with the supporting levers, and two ratchet standards with the axle, in such a manner that the driver can at pleasure vary the depth of furrow on either side of the tongue independently; fourth, in the combination of an auxiliary frame with the tongue, and with an arched coupling-bar, so that the auxiliary frame is free to vibrate on its hinged coupling, and the width of ploughing can be adjusted on the arched bar; fifth, in hinging the auxiliary frame to the tongue, between the evener and neck-yoke, to increase the length of beam and obtain more purchase in the side motion; sixth, in the adjustable support for the driver's feet combined with the auxiliary frame; seventh, in the eye-bolt, which admits a vertical adjustment of the standard, and permits it to move back, when its wooden connecting pin is broken, without injury to the plough; eighth, in the combination of the double eye-bolted standard block with the auxiliary frame, so that the standards can be vertically adjusted and swing free when encountering a rigid obstruction.

Two carrying-wheels, A and B, support a bent axle, C, to which, upon a raised bracket, a, the tongue D is rigidly secured, and centrally stayed by brace-rods 1 and 2. These parts alone constitute the main frame of our cultivator. The tongue D projects far enough beyond the axle C to support, on its rear end, a properly-placed driver's seat, b; and the tongue may be flexible or rigid, and consist of one or more pieces. Near each end of the axle standards c and c' are secured, which carry friction-rollers in mortises at their top; and upon the axle two curved rack-bars, d and d', are fastened near the standards c and c'. In front of the axle, and upon either the upper or lower side of the tongue, a cross-piece, E, is securely fastened, having its ends turned up, and connected by brace-rods, 3 and 4, to the upper ends of the segment racks d and d'; the segment racks being secured to the standards by rods 5 and 6; thus the standards and segments are rendered rigid, and are secured in a vertical position upon the axle. Upon the turned-up ends of the cross-piece E are pivoted levers, F and F', which are mortised to receive the rack-bars, upon which the levers have a free vertical movement; but the levers can be fixed by spring bolts, which enter between the teeth of the rack, and the bolt can be withdrawn, when the lever is to be depressed or raised, by the hand of the driver; a short handle, e, being pivoted on each lever close to its handle, and the short handle e being connected to the spring-catch by its draw-rod. Caps, f and f', over the springs, serve to protect them against becoming injured or clogged with dirt. Chains or cords are attached to the upper sides of the levers, and are passed over the friction-rollers in the standards c and c', and are connected by rods, 7 and 8, with the auxiliary frame; and this arrangement enables the driver to raise either lever independently of the other, or both together; thus he can regulate the depth of furrow at will while passing over uneven ground. The auxiliary frame is composed of two beams, H and H', that are either pivoted or rigidly fastened to a collar or yoke, G, which is fastened to the tongue by a staple that leaves the frame free to vibrate. The beams H and H' pass far enough behind the axle to receive one or more ploughs or cultivator teeth on each beam, and the beams are spread apart the distance best adapted to the work required of the cultivator, and they are connected together by an arched coupling-bar, K; the bar and beams being fastened together by screw staples, h, as shown in fig. 1 in preference to passing screw-bolts or pins through the beams. To adjust the ploughs transversely to adapt the cultivator to different crops, it is only necessary to loosen the staples, shift the beams upon the arched bar, and tighten the staples again. The ends of the arched coupling-bar project beyond the outside of the beams far enough to admit of the rods 7 and 8 passing through

holes in the bar, where the rods are so secured as that, when the levers F and F' are depressed, the ploughs will be raised out of the ground, and the rear portion of the auxiliary frame will be supported by the axle, and the front part of the frame will be supported by the tongue; but when the levers are raised the frame can be depressed to any distance necessary for the ploughs to enter the ground. The extent of this adjustability is such that at times the driver would be incommoded for want of a proper support for his feet. Tall and short persons also require foot-supports of different heights. To obviate these objections to one fixed foot-support we have invented an adjustable shoe that can be raised as the auxiliary frame is lowered, which will also accommodate drivers of different heights. Ratchet bars, L, are fastened in any proper manner to the beam in such relation to the driver's seat as is most convenient for the driver, one being shown at fig. 1, where a metal shoe, M, has a box at its heel that fits neatly on the bar, to which the shoe is held by a wedge, 9, placed between the rear of the box and the bar, the front of the box being provided with one or more projections that can be made to fit in the notches of the ratchet bar, and of course, when the wedge is raised, the shoe can be shifted or raised from one notch of the bar to another until the shoe is at the proper height to support the driver's feet, who is thus enabled to ride at ease, and measurably control the side movement of the ploughs. The ploughs or cultivator teeth are secured to the bottom of standards, O, while the upper ends of the standards pass through an eye, P, swivelled in a socket or double block, Q, secured to the beam of the auxiliary frame. Each standard carries a link or ring, i, secured by a staple in rear of the standard, and the link or ring i is coupled to a stay-rod, k, by a wooden pin, the forward end of the rod being secured to the beam of the auxiliary frame. The upper end of the standard O slides up and down in the eye P, and can of course be secured at any height desired. The eye P has a shank, p, that passes through the socket Q and the beam, and is secured by a nut, r, thus forming a double block, and the eye, whilst permitting a vertical movement to the standard, is capable at the same time of rotating in its socket, and then, when the plough encounters a rigid obstruction, the wooden pin, which couples the ring or link with its brace-rod, breaks, and the standard is free to move back, and thus the plough remains uninjured. The standard thus secured obviously will permit the plough to be turned at any angle desired for throwing the land either to or from the crop; will enable the plough to be held at any height from the ground to regulate the depth of ploughing, and at the same time will permit the plough to encounter a rigid obstruction without being broken, while the easy, but limited side movement of the auxiliary frame enables the driver measurably to so control its action as to cultivate with safety those crops which have been irregularly planted, or which may have come up in other than straight lines. From its great mobility our cultivator performs a variety of work effectively, and with great ease to the team and the driver.

What we claim as our invention, and desire to secure by Letters Patent, is—

1. The combination, substantially as described, of the tongue with the axle, arranged as set forth, for the purpose specified.
2. The combination with the tongue of the single cross-piece E, so arranged as that it shall serve as a brace for the segment, and a fulcrum for the levers that control the auxiliary frame.
3. The combination of two spring bolts with two supporting levers and two ratchets, and with the axle, arranged and operating substantially as and for the purpose set forth.
4. The combination of the rigid frame with the auxiliary frame, when the former is hinged to the latter, substantially in the manner and for the purpose described.
5. The combination of the auxiliary frame with the tongue, when the former is hinged to the latter, substantially as and for the purpose set forth.
6. The combination of an adjustable support for the driver's feet with the auxiliary frame, substantially as and for the purpose set forth.
7. The swivelled eye-bolt or double block, constructed, arranged, and operating substantially as and for the purpose set forth.
8. The combination of the eye-bolt and standard with the beam of the auxiliary frame, substantially as and for the purpose set forth.

In testimony whereof we have hereunto subscribed our names.

T. F. BERTRAND,
PETER SAMES.
